UNITED STATES PATENT OFFICE.

FREDERICK BAIER, OF ANDERSON, INDIANA.

IGNITION APPARATUS.

1,366,887.

Specification of Letters Patent. Patented Jan. 25, 1921.

Application filed March 30, 1918. Serial No. 225,783.

To all whom it may concern:

Be it known that I, FREDERICK BAIER, a citizen of the United States, residing at Anderson, in the county of Madison and State 5 of Indiana, have invented certain new and useful Improvements in Ignition Apparatus, of which the following is a specification.

This invention relates to an ignition apparatus for internal combustion engines 10 which is particularly adapted to be used in connection with internal combustion engines in automobile construction, the invention having particularly to do with certain means for automatically advancing and retarding 15 the ignition, containing many refinements in construction over my earlier patent issued to me on November 14, 1916, No. 1,204,730, and also including several new features for increasing the efficiency and production of 20 power of such engines.

One of the objects of the invention is to provide a construction for controlling the ignition in internal combustion engines, in which unnecessary vibration between the 25 parts is largely overcome, thereby insuring more positive action which is reflected in a more uniform running of the engine when subjected to varying loads.

A further object of the invention consists 30 in constructing the device for controlling the electric current in the ignition system of internal combustion engines so that the contact-points will wear uniformly, and maintain a uniform flow of the current.

A still further object of the invention consists of means for simplifying the transmission 35 of the primary current to the contact-points, which not only eliminates the usual springs and rivets, but renders the construction more simple, lending effectiveness 40 throughout the entire range of the timing device.

A still further object of the invention consists in the provision of means for initially 45 setting and re-setting the mechanism for timing or interrupting the electric current in ignition systems of internal combustion engines, without removing any of the parts, the device being susceptible of fractional 50 adjustments for advancing or retarding the time of ignition, as conditions may dictate.

A still further object of the invention consists in the provision of means whereby tension 55 may be easily and quickly increased on the governor mechanism which controls the

interruptions in the electric current of ignition systems employed in connection with internal combustion engines.

A still further object of the invention consists in simplifying the construction of 60 means for controlling the interruption in the electric circuit of ignition systems in internal combustion engines, thereby effecting economy in manufacture, and efficiency in operation.

To accomplish the above objects of the invention, and such others as may appear from a perusal of the specification and claims, by means of the construction illustrated in the accompanying drawings, forming a part 70 hereof, in which—

Figure 1 is an exterior view of one side of the distributor casing, showing the induction coil attached thereto. Fig. 2 is a top or plan view of the construction shown 75 in Fig. 1. Fig. 3 is a top or plan view of the internal movable parts of the distributor, in which the cap is omitted. Fig. 3^a is a fragmentary detail sectional view on the line 3^a—3^a in Fig. 3. Fig. 4 is a central vertical sectional view through the casing and movable parts of the distributor. Fig. 4^a is a fragmentary detail sectional view through one end of the cap and cable socket, showing the means for holding the cables in 80 position. Fig. 5 is a top or plan view of the internal mechanism of the distributor, in which the interrupter-frame and distributor-arm are omitted. Fig. 6 is a fragmentary detail vertical sectional view, on 85 the line 6—6 in Fig. 4. Fig. 7 is a horizontal sectional view through the governor mechanism, on the line 7—7 in Fig. 4. Fig. 8 is a top or plan view of the interrupter-frame and actuator-cam, in which the remaining parts of the distributor are omitted. Fig. 9 is a side elevation of the construction 90 shown in Fig. 8, except that the actuator-cam is omitted. Fig. 10 is a side elevation of 95 the actuator-cam. Fig. 11 is a horizontal sectional view of the actuator-cam, on the line 11—11 in Fig. 10. Fig. 12 is a side elevation of the distributor-head, the remaining parts being omitted. Fig. 13 is a central vertical sectional view of a modified 100 construction of the spring securing disk, on the line 13—13 in Fig. 14. Fig. 14 is a top or plan view of the construction shown in Fig. 13. Fig. 15 is a top or plan view, on an enlarged scale, of the distributor casing, show- 110

ing more clearly the construction and arrangement of the cam and interrupter frame, the remaining parts being omitted. Fig. 16 is a fragmentary detail sectional view on the line 16-16 in Fig. 17. Fig. 17 is a fragmentary detail sectional view on the line 17-17 in Fig. 15. Fig. 18 is a modified construction of the distributor when the spring securing disks are supported upon a division 10 wall in the distributor casing.

Referring to the drawings, the movable parts of the distributor are arranged within a suitable hollow bowl or casing 20 having a depending stem 21 which is secured to the engine frame by means of the bolts 22. Stem 21 is provided with a longitudinally extending aperture adapted to receive a driving shaft 25 which is driven from the engine shaft, not shown. Secured to and rotating 15 with shaft 25 is a channeled box 26, and arranged on opposite sides of shaft 25 and moving in the channels of box 26 is a pair of centrifugally actuated governor-weights 27, the object of which will be hereinafter 20 described.

The upper end of shaft 25 is provided with a loose sleeve 35, and said sleeve is provided with an integral cam 36 adapted to actuate interrupter-frame 37. The lower end of 25 sleeve 35 is provided with an integrally formed disk 38 which is provided in its opposite peripheral sides with teeth 39 and 40. See Fig. 10. To determine the relative positions of the governor-weights 27 when sleeve 35 is placed into position, disk 38 on said sleeve is provided with an integral lug 38^a which is adapted to pass through a slot in one of the governor-weights 27, as clearly shown in Fig. 5.

40 The centrifugally actuated governor-weights 27 are provided with respective extensions 41 and 42, and these extensions are provided with the respective teeth 43 and 44, in which teeth 39 mesh with teeth 43 in extension 41 and teeth 40 with teeth 44 in extension 42. By means of this construction it becomes obvious that when the speed of the engine reaches a point where the rotation of shaft 25 is sufficiently high to cause 45 governor-weights 27 to move radially away from the axis of shaft 25, the engagement between the governor-weights 27 and sleeve 35, will cause cam 36 to move forward about its axis to bring its contact-points into engagement and actuate interrupter-frame 37 at 50 an earlier period of time, with corresponding earlier interruptions in the primary circuit. When the speed of the engine is reduced a corresponding retardation in the 55 interruptions in the primary circuit occurs. To prevent premature radial movement of governor-weights 27, before the engine has attained a predetermined speed, is accomplished by passing a spring 45 through an 60 alined aperture 46 in the two governor-

weights 27 and securing one end of said spring to one of the governor-weights by means of a cross-pin 47, and the other end of spring 45 with the second governor-weight by means of a wedge-shaped key 48, having 70 a serrated edge adapted to engage the looped end of said spring. By moving key 48 longitudinally the length of spring 45 may be increased or decreased and thereby vary the tension applied to the governor-weights 27, 75 as the necessity requires. In addition to the effect exerted by spring 45 in pulling governor-weights 27 toward each other, I employ a pair of springs 49 for slightly opposing the pressure applied by spring 45, in 80 order that the governor-weights will be constantly under partial restraint and their movements controlled, as the force and effect of the springs and centrifugal action are modified under varying conditions. 85

As shown in Fig. 3 of the drawings interrupter-frame 37 surrounds cam 36, and said frame is provided with an actuator-point 51, composed of fiber or similar insulating material to prevent the current from being 90 grounded at this point. After the points of cam 36 contact and move interrupter-frame 37 to break the primary circuit, by opening a gap between contact points 53 and 54, the interrupter-frame 37 is returned to normal 95 through a spring 55. Spring 55 may be formed of one or more leaves, and is preferably secured at its center to interrupter-frame 37, the free ends of said spring being 100 properly secured by certain means which will now be described.

In order to simplify and reduce the cost of manufacture of my present distributor, I dispense with the usual horizontal division wall 30 for mounting the operative parts, as 105 shown in the modified construction in Fig. 18, and employ lugs 56 and 56^a, as shown in Fig. 3. These lugs may be cast integrally with the distributor-casing or, for convenience of manufacture, may be cast integral 110 with a sleeve 56^b, the latter to be slipped downwardly into the hollow portion of the casing and riveted fast to the casing-wall. Each of the lugs 56 is provided with a circular socket 57, and extending from each 115 socket to the edge of the lugs are the slots 59 forming passageways for introducing the ends of the spring 55. Each socket 57 is also provided with a marginal recess 58 adapted to provide sufficient clearance for 120 the ends of spring 55. Arranged within each socket 57 is a centrally located removable screw 60, and each of these screws is provided with a swiveled-head 61 having kerfs to receive the end of a screw-driver 125 for setting the screws and for rotating the swiveled-heads after the screws are set. The connection between the swiveled-head 61 and screws 60 is sufficiently close fitting to enable the two to rotate in unison until the 13

screws are firmly set, after which heads 61 are free to rotate independently of the screws to permit the ends of spring 55 to be clamped between the heads and adjacent 5 walls of the sockets 57. To permit the initial introduction of the ends of spring 55 between heads 61 and adjacent walls of sockets 57, a part of the peripheries of heads 61 is cut away to give the necessary clearance, when said heads are moved into proper 10 position.

Interrupter-frame 37 terminates at one end in a U-shaped frame 65 (Fig. 8) in which the fiber actuator-point 51 is secured, 15 and to enable frame 37 to advance its position for maintaining actuator-point 51 in contact with cam 36, when the former becomes worn, I provide the exterior side-walls of frame 65 with horizontal channels 20 66 which receive the pivot forming balls 67 which are arranged in the upper ends of standards 68, and the pivotal connection thus formed permits interrupter-frame 37 to move longitudinally for maintaining contact between actuator-point 51 and cam 36. 25 Standards 68 are supported upon lugs 56 formed on casing 20. Mounted beneath U-shaped frame 65 and between standards 68 is a horizontally disposed lever 70 which is 30 pivoted at 71 to the base of the standards, and in normal position its outer end 73 contacts and holds a vertical spring 76 out of contact with the adjacent end of fiber block forming the actuator-point 51, as clearly 35 shown in Figs. 3 and 16. As actuator-point 51 wears down interrupter-frame 37 moves toward cam 36 until lug 75 contacts and oscillates lever 70 a sufficient distance to cause its outer end 73 to release vertical spring 40 76. When spring 76 is released its free end bears against the adjacent end of the fiber block and exerts sufficient tension against the end of interrupter-frame 37 to cause contact point 53 to maintain proper contact 45 with stationary contact-point 54, on the distributor casing 20.

Arranged upon the upper end of sleeve 35 and rotating therewith is a distributor-block 80 composed of insulating material, 50 and said block carries a distributor-arm 81 which is adjustably held in position on said block by means of a screw 83. To enable distributor-block 80 to be easily and properly located, I provide a recess 35^a in the 55 upper edge of sleeve 35 (Figs. 8 and 10) which recess receives a lug 80^a on said distributor-block 80. See Fig. 12. To hold distributor-block 80 in proper alignment with sleeve 35, said distributor-block is provided with a depending shaft 82 which enters the hollow portion of sleeve 35.

The moving parts of the device are inclosed by means of a suitable cap 85 having a sufficient number of openings 88 corre-

sponding to the number of cables 91 required to supply the number of cylinders employed in the engine. The high tension current enters through cable 86, and passes down to distributor-arm 81 through a flexible brush 87, the current being distributed by said distributor-arm to the several electrodes 90 where it passes out through cables 91, to the spark plugs of the engine not shown. Cap 85 is held in operative position on the upper end of casing 20 by means of a spring 95 (Fig. 2), the said spring being bent outwardly as indicated at 96 and when rotated the points 96 may be brought under the hooks 97 formed on the standards 98 secured to casing 20. To prevent cap 85 from turning when spring 95 is placed in position the said cap is provided in its marginal edge with a recess 100 adapted to receive a prong 101 formed out of one of the standards 98. See Fig. 1.

To prevent the end of cables 91 from being accidentally displaced from openings or sockets 88 in cap 85 and still enable them to be readily removed and re-inserted when desired, I provide certain simple thin metal shells 105 (Fig. 4^a) having one end closed, and these shells are inserted into sockets 88 with the closed ends of the shells at the bottom and arranged to rest upon and effect electrical connections with electrodes 90. Formed on the side wall of each shell 105 are two or more tongues 106, which are arranged with their free ends projecting downwardly so that said free ends of the tongues will engage the insulating coating of the cables 100 and necessitating a little force to be applied to disengage the cable ends from said sockets 88. To insure a proper electrical connection to be maintained between the ends of cables 91 and electrodes 90, I mount 105 a metallic needle 107 in the bottom and centrally of each shell 105, which needles penetrate the metallic cores of the cables.

In Figs. 13 and 14 of the drawings I have shown a modified construction for securing the ends of springs 55, in which the screws 60 are formed conically for expanding open collars 108 and clamping the ends of springs 55 against the adjacent walls of the sockets 57, and to prevent rotation of collars 108 when screws 60 are rotated, I form tongues 109 from the walls of lugs 56, and then bend down said tongues so as to project between the open split ends of collars 108, as shown in Fig. 14, or by a pin 110 shown in Fig. 18.

In the modified form shown in Fig. 18, I have shown my distributor provided with a horizontally disposed conventional division wall 30 for mounting the supports for the movable parts, thereby providing additional means for meeting varying trade conditions. In this construction I provide a standard 125 54^a for carrying the stationary contact-point

54, and this standard 54* with standards 68 and lugs 56 are all mounted upon division wall 30.

Examining Figs. 1 and 3 of the drawings, 5 it will be noted that a coil 111, which is necessary in using this style of distributor, is arranged exteriorly and in close proximity of the casing 20 and stem 21, said coil being held in position between the ends of a pair 10 of connecting bars 112 which are secured to ears 113 formed on the exterior lower surface of casing 20, by means of suitable bolts 114. Coil 111 is electrically connected with stationary contact-point 54 by means of a 15 low tension cable 115, the high tension current passing out through connection 116 into the high tension cable 86 where it is delivered through the flexible brush 87 to the distributor-arm 81. Coil 111 is also connected to a suitable source of electrical 20 energy (not shown) by means of a cable 117. It will be noted by the hereinbefore described construction that coil 111 and distributor-casing 20 are arranged in close relation, and readily accessible, their arrangement being such that each can be individually inspected and repaired without disturbing the mechanism of the other, as oftentimes happens where the coil is arranged 25 within casing 20 and below the working parts of the distributor, thus necessitating the removal of the moving parts of the distributor to gain access to the coil.

The time of contact between cam 36 and actuator-point 51 may also be manually advanced and retarded, and this I accomplish by removing screw 32 from slot 33 and attaching a lever 120, as shown in Fig. 18. The outer end of lever 120 is connected to 40 a suitable actuator rod which extends to and is operated by the usual spark control lever on the steering wheel.

Having thus fully described my said invention, what I desire to secure by Letters 45 Patent, is—

1. In an ignition apparatus, a driving shaft, a cam loosely arranged on said shaft, an interrupter-frame actuated in one direction by said cam, means for imparting tension for returning said frame to normal, a spring normally held out of engagement of said interrupter-frame, spring-release means for normally holding said spring away from said frame, and means carried by said frame 55 for actuating said spring-release means for releasing the spring at a predetermined time.

2. In an ignition apparatus, a driving shaft, a cam loosely arranged on said shaft, an interrupter-frame actuated in one direction by said cam, springs for returning said frame to normal, stationary lugs having sockets for receiving the ends of said springs,

and revoluble means arranged within said sockets for impinging the ends of the springs } against the adjacent walls of the sockets. } 65

3. In an ignition apparatus, a casing, a driving shaft in said casing, a cam loosely arranged on said shaft, an interrupter-frame actuated in one direction by said cam, springs for returning said frame to normal, 70 lugs supported by said casing and having sockets for receiving the ends of the above springs, open-collars arranged in said sockets, and means for expanding said collars to impinge the ends of the springs 75 against the adjacent walls of the sockets.

4. In an ignition apparatus, a driving shaft, a cam loosely arranged on said shaft, an interrupter-frame provided with longitudinally extending channels and actuated 80 in one direction by said cam, a pair of standards, means arranged in said standards and extending into said longitudinal channels to form a slidable pivotal bearing for said interrupter-frame, a contact-point carried by 85 said interrupter-frame, a stationary contact-point alined with the contact-point on the interrupter-frame, and a tension device exerting pressure against the interrupter-frame for maintaining a contact between 90 the contact-point on said frame and stationary contact-point when the interrupter-frame is free of the cam.

5. In an ignition apparatus, a driving shaft, a cam loosely arranged on said shaft, 95 an interrupter-frame actuated in one direction by said cam, means for returning said frame to normal, a pair of centrifugally actuated governor-weights rotating with and having independent radial movement of said 10 driving shaft, a spring for returning said weights to normal when the driving shaft is at rest, and a longitudinal movable key for varying the length of the spring and changing its effective resistance to the movements of the weights. 10

6. In an ignition apparatus, a driving shaft, a cam loosely arranged on said shaft, an interrupter-frame actuated in one direction by said cam, means for returning said frame to normal, a pair of centrifugally actuated governor-weights rotating with and having independent radial movement of said driving shaft, a spring for returning said weights to normal when the driving shaft 1 is at rest, and a longitudinal movable key for keeping the spring extended for maintaining a slight resistance to the movements of the weights.

In witness whereof I have hereunto set 1 my hand and seal at Indianapolis, Indiana, this 27th day of March, A. D. one thousand nine hundred and eighteen.

FREDERICK BAIER. [L. S.]
